ADJUSTABLE SUPPORT

Leon Boltuch, Bronx, N. Y.

Application April 26, 1950, Serial No. 158,311

15 Claims. (Cl. 248—123)

1

The present invention relates generally to an adjustable bracket of the type which permits of adjusting the position of the load carried by the bracket to substantially any point within a sphere whose diameter is defined by the longest dimension of the bracket. More particularly, the present invention relates to this type of adjustable bracket which is designed to support a relatively light load which is best illustrated in the present application by a desk lamp. It will be understood that while the invention is illustrated herein as embodied in a desk lamp in which an illuminating unit, whether in the form of a conventional electric bulb or in the form of a tubular discharge lamp together with a shade or reflector therefor, constitutes the load, the invention may be employed in adjustably supporting a variety of loads. It will, therefore, be understood that wherever the present specification speaks of a lamp, or a desk lamp, or a table lamp, or an illuminating unit, the language is merely illustrative and is intended to include a variety of other types of loads whether they be in the form of hand tools or electrically driven tools or other such devices.

Essentially the present invention contemplates a base, a bracket carried by the base, and a load carried by the free end of the bracket; the bracket having a universal movement with reference to the base thus permitting for the adjustment of the position of the load unit in any position desired with reference to the base.

One of the objects of the present invention is to provide in an organization of the type described means which firmly maintain the load unit in its adjusted position, while at the same time the means operates to permit movement of the load unit with great facility from the adjusted position of any other desired position.

Another object of the invention is that the means which serves to maintain the load unit in its adjusted position also operates to assist in the movement of the load unit once the movement is set into operation.

A still further object of the invention is to provide counterbalancing means which serve to counterbalance the leverage of the load unit in any selected position without imposing any frictional burdens upon the pivotal connections of the parts involved.

In the specific embodiment of the present invention shown herein, the bracket is jointed and is universally mounted on the base. It is the aim of the present invention to provide counterbalancing means for the leverage of the load unit

which does not impose any burdens upon the joint between the two arms of the bracket nor upon the universal pivot of the bracket upon the base.

5 Another object of the present invention is to provide the cooperation of friction and a spring for counterbalancing the load in any selected position, without subjecting the joints or pivots of the bracket to any undue stresses.

10 Having thus described the general objects of the present invention, reference is now had to the following specification and the accompanying drawings for a full and clear disclosure of all the details thereof, it being understood that these are merely illustrative and that variations thereof falling within the scope of the appended claims will be apparent to persons skilled in the art.

Fig. 13 is a perspective view of one of the tubular arms.

35 Figs. 14 to 17, inclusive, illustrate the critical positions of the load unit.

In its broad aspects, the present invention comprehends a base, a pair of jointed arms forming

40 a bracket universally mounted on the base, and a lamp unit or the like, universally mounted on the free end of the bracket.

An important phase of the present invention resides in providing within the bracket devices which operate to exert the desired force to support and counterbalance the bracket and lamp unit in any desired position, the same force also serving to assist in a movement of the lamp unit from one adjusted position to another; the essential characteristic of the organization being that

45 the operating force does not involve the universal mountings nor the joint between the arms of the bracket with the consequence that the lamp unit is supported in a free floating manner and the life of the apparatus is lengthened.

Essentially, the present invention employs for this purpose a slidable friction element and a resilient power storage element both disposed within the tubular arms. These elements are merged into a single force by means of a linkage which is connected to the friction element and by-passes the resilient power storage element and the adjacent joint. The friction element takes the form of an elongated split resilient friction sleeve disposed within the tubular arms of the bracket. The resilient power storage element is in the form of a helical spring disposed within each of the tubular arms and pressing against the friction sleeve. The linkage is in the form of a rigid rod-like element attached at one end to the friction sleeve and at the other end to the base or another adjacent portion of the bracket.

The linkage element virtually merges the passive frictional resistance of the friction element with the active power stored within the helical spring into a single effective force which provides a virtually floating support for the lamp unit and which also serves to retain the lamp unit in any adjusted position.

With the above general statement of the principles involved in the present invention, we may now turn to a description of a preferred and specific embodiment.

In the drawings 12 illustrates a lamp housing which in the present case is of the type which houses a pair of luminescent discharge tubes. The lamp unit 12 is carried by a pair of jointed arms 13 and 14 pivoted to each other at 15. The inner arm 14 is universally mounted on the base 16. Thus, by means of this organization, the lamp unit 12 may occupy substantially any position within the sphere having the overall length of the arms 13 and 14 as its diameter. Thus the lamp unit 12 may be moved with the outer arm 13 about the pivot 15 to a position in which the lamp unit illuminates the area closely adjacent to the base 16. This is illustrated by the dotted line position A of the outer arm 13. If desired, with the arms 13 and 14 in substantial alignment the arm 14 may be extended as indicated by the dotted line position B, thus providing illumination of an area far removed from the base 16. In addition, the lamp unit 12 swings vertically about the pivot 11 and also swings laterally about the line 18. Thus the lamp unit has a universal movement about the free end of the bracket and also has universal movement about the base 16.

The universal pivotal mounting of the inner bracket arm 14 upon the base 16 comprises several cooperating elements. One of these elements is a stud 20 having an enlarged circular base 21 with a pair of diametrically opposed and interiorly threaded passages 22 to receive the screws 24 for mounting the stud on the base 16 as shown in Fig. 1. The base 16 may be of any suitable shape, but is preferably substantially hollow so as to provide for mounting therein transformers or ballast units or switches and other such devices as are associated with a lamp unit of the type described. This base 16 provides a table-like plate 17 to receive the stud 20. The table plate 17 is provided with an aperture which registers with the axial passage 25 in the stud 20 to provide a passage for electric cord through the bracket. The stud 20 is provided with an annular channel 26 as shown. The channel 26 receives a lug from the two-part housing 28 which is mounted upon the stud 20 and firmly secured thereon. The two-part housing 28 thus may rotate about the stud 20. It is de-

sired, however, to limit the rotation around the stud 20 in order to minimize the possibility of injuring the electric cord which passes through the bracket. For this purpose, therefore, the channel 26 does not extend throughout the 360° but is provided with an interruption which serves as a shoulder to limit the rotational movement of the housing 28 upon the stud. The upper half of the stud 20 is preferably of frusto conical shape as shown and is designed to fit snugly within the housing 28 which has a corresponding interior surface 39 resting upon frusto conical surface of the stud so as to provide firm support for the housing and bracket and still permit the lamp unit and bracket to rotate about a vertical axis.

The two-part housing 28 consists of two complementary halves which may be die cast. In their lower portions the two parts of the housing are each semi-annular and have dove-tailing or inter-engaging portions 38 and 21. These lower portions of the two halves of the housing, therefore, form a solid annulus about the intermediate portion of the stud 20. One of the halves has a lug 31 projecting inwardly which enters the channel 26. The complementary dove-tailing or inter-engaging portions are provided with passages which together form a pair of continuous passages 32. In the assembly of the present device, the two parts of the housing 28 are placed in an embracing position around the stud 20 and adjusted to a position where the passages 32 register with the passages 22 in the stud. Pins or pintles 33 are then driven into the passages 32 and serve to unite the two halves of the housing firmly and solidly around the stud 20 while at the same time permitting of rotation of the housing around the stud 20, the lug 31 serving to engage the stop in the channel 26 and thereby limit this rotational movement.

The upper portion of the housing 28 comprises a pair of dished plates 34 which have inwardly directed annular flanges 35. Each half of the housing also has a curved arm 36 each having a notch 37 at its free end as shown.

The hinge unit 40 consists of an annular portion 41 and a tubular extension 42 integral therewith. The passages in the parts 41 and 42 are in communication and form a continuous passage for the electric cord. The ends of the ring 41 are rabbeted as shown at 43 for seating the same on the flanges 35 in the corresponding halves of the housing 28.

It will now be understood that the universal pivot consists of the stud 20, the two-part housing 28, and the hinge unit 40. In order to assemble these parts together, the two halves of the housing are brought together in a manner to embrace the stud 20 as previously described and at the same time have the flanges 35 enter the rabbets 43 in the ring 41. Under these conditions the dove-tailing inter-engagement of the parts of the housing 28 provide the passages 32 which then receive the pins or pintles 33 thereby firmly assembling these several parts together and permitting of rotation about a vertical axis of the housing with reference to the stud and of rotation about the horizontal axis of the hinge unit. After this assembly is completed, the clips 46 are inserted as shown in order to hold the upper part of the housing in firm assembled relation. Thus the housing unit 28 rotates about the stud 20 and the hinge unit 40 rotates within the housing 28 about a horizontal axis. The bracket arm 14 which is received by the tubular portion 42 of the hinge unit 40 thereby has universal move-

ment with reference to the stud 20 and the base 16 upon which it is mounted.

The ring 41 is provided with an opening which permits the electric cord to enter through the passage 25 in the stud, the cord also entering from the ring 41 into the tubular portion 42 and into the tube 14. The wall of the tubular portion 42 is preferably provided with a pair of opposite and inwardly projecting thick stops 45. The stops 45 serve as rests for tubular arm 14. The tubular bracket 14 fits snugly and firmly within the tube 42 and is provided at its end with a pair of bottom slots 62 which slide over the lugs 45, and the tube or arm 14 is thereby maintained firmly in position and against rotation.

Disposed within the tubular bracket arm 14 is an elongated resilient split sleeve 51 made of spring steel. This sleeve presses resiliently and firmly against the inner face of the tubular arm 14 and exerts considerable friction. The finger 52 integral with the sleeve 51 projects laterally from the tube through an elongated slot 53. The coil spring 50 is disposed within the tube 14 between the sleeve 51 and the lugs 45 at the lower end of the tube 14. If desired, an annulus 54 may be interposed between the upper end of the spring 50 and the lower end of the resilient sleeve 51 so as to provide for the uniform transmission of the force of the spring 50 to the sleeve 51.

A slider 56 having an arcuate inner face which slides over the outer face of the tubular arm 14 is provided with a slot 57 which receives the finger 52 and is firmly riveted thereto by the rivet 58. The inner face of the slider 56 is provided with a groove 59. The link 60 is made of a metal rod bent into the shape as shown, thereby providing one loop which enters the notch 37 in the arm 36 of the housing 28 and another loop at the end which enters the notch 59 in the slider 56. The link 60 thus serves to position the resilient sleeve 51 and to hold the spring 50 in a compressed condition.

The counterbalancing force provided by the organization thus far described comprises a fixed frictional force and a variable resilient pressure. The resilient pressure increases with the departure of the bracket arm from the vertical, and this increased force is available as the moment of the load grows. The same resilient pressure operates to move the friction sleeve and bracket arm when the load is being guided manually from one position to another. Thus as the arm 14 is moved from the vertical position to the horizontal position a constantly increasing active resilient pressure of spring 50 is added to the fixed frictional resistance of the sleeve 51 to produce the necessary force for counterbalancing the moment of the load. This is caused by the transmission of the movement of the arm 14 to the sleeve 51 through the link 60 and the resultant compression of the helical spring 50.

Having described the manner in which the arm 14 is universally mounted on the base 16, the following portion of the specification describes the structure of the joint 15 between the upper end of the inner bracket arm 14 and the lower end of the outer bracket arm 13. The joint 15 consists of a two-part housing 64 and a hinge ring 65 which is embraced by the housing 64 and rotates within the housing 64 about a horizontal axis. The housing 64 comprises a downwardly extending tubular portion 66 which

receives the upper end of the inner bracket arm 14. The housing has a pair of inwardly directed lugs 67 which are received by corresponding slots 68 in the upper end of the tube 14. The tubular portion 66 curves as shown and carries at the upper end a pair of plates 69 which have inwardly directed annular flanges 70. The housing also has the arm 71 which is provided with a notch 72 as shown. The two parts of the housing are held together by assembly clips 73.

The hinge ring 65 comprises the annular portion 75 which is rabbeted on each face at 76 and an outwardly extending tubular portion 77. The ring portion 75 is embraced by the two halves of the housing with the ring 75 rotatably mounted on the flanges 70. The tube 77 receives the tubular bracket or arm 13 and is provided with a pair of integral lugs 78 which are received by bottom slots in the arm 13 to prevent rotation of the arm. The portion 75 has an opening as shown for the passage of the electric wire.

It will now be understood that when these several units are assembled together, the tube 66 of the housing 64 becomes fixed with the tube 14, and the tube 13 becomes fixed with the tube 77, and by means of the rotary engagement between the ring 75 and the housing 64 the bracket arm 13 is jointed to the bracket arm 14 and is pivoted thereto about a horizontal axis.

It is preferred that the arms 13 and 14 should move in the same plane as shown. Like the arm 14 as previously described, the arm 13 is similarly provided with a coil spring 50 and the resilient friction sleeve 51, which are operated on by the link 60 carried by the notch 72 in the housing 64 and the notch 59 in the slider 56 which is affixed to the projected finger 52.

The coil spring 50 and resilient friction sleeve 51 in the upper bracket arm 13 cooperate with each other and with the link 60 as previously described and serve to counterbalance the leverage of the lamp unit 12 about the joint 15.

The upper end of the arm 13 is jointed to the lamp unit 12 by means of a universal mounting which in its essential respects is identical with the universal mounting interposed between the arm 14 and the base 16. It comprises a stud 20 as previously described and a two-part housing 80 which embraces the stud 20 in the same manner as the housing 28 and cooperates therewith in the same manner and thus provides for rotation of the stud 20 within the housing 80. At its outer end, however, the housing 80 is provided with the rabbeted annular ring 81 which is received and embraced by the plates 82 with the rabbeted portion riding on and rotatable on the interior flanges 83 on said plates. The plates 82 are carried by the tubular element 84 which receives the free end of the tube 13. The stud 20 is mounted on lamp unit 12. Thus lamp unit 12, together with the stud 20, may be rotated within the housing 80 and similarly the lamp unit 12, together with the housing 80, may be rotated between the plates 82 about another axis. In addition, it is desirable also to provide rotation for tube 84 on tube 13 so that the load unit 12 with the intermediate elements 20, 80 and 84 should be free to rotate on the tube 13, to an extent short of 360°. For this purpose the tube 84 has an annular innerchannel 85 which does not extend around the full circle, and tube 13 is provided with a lug 86 that rides in the channel 85 and is stopped at the ends of the channel.

75

It will now be seen that the present organization provides a desk lamp in which the illuminating unit may be moved so as to provide desired illumination over any portion of a large area without moving the base upon which the bracket and illuminating unit are supported. For this purpose in the present organization the illuminating unit is universally movable with reference to the bracket and the bracket and illuminating unit together constitute an organization which is universally movable with reference to the base. In addition, the jointed bracket with the counterbalancing devices carried interiorly of the brackets serve to maintain the illuminating unit in any adjusted position and permit of the ready movement of the unit to any desired position. This is all accomplished without imposing any undue strains upon the several joints and pivots in the bracket and support.

The resilient internal friction sleeves 51 are long lasting and operate to eliminate the necessity for friction at the pivoted joints. These sleeves 51 with the helical springs 50 may be disposed within a tubular arm which may have an internal diameter less than a half inch, thus permitting the use of slender and attractive tubular arms.

In operation only a slight manual pressure on the lamp overcomes the internal pressure of the sleeves 51, and in effect the operator needs only to direct the lamp to the desired position, the work of moving the lamp being provided by the springs.

The helical springs 50 exert their pressures axially of the tube and in line with the pivotal joints. Thus these springs do not exert directly any moment or leverage about any pivot or joint. On the other hand these springs exert considerable pressures against the friction sleeves 51. These pressures, together with the frictional resistance of the sleeves, serve to overcome the moments of the load or illuminating unit about the pivotal joints, oppose the downward movement of the load and retain it in any adjusted position. On the other hand when the user applies but slight directive manual pressure to the load unit in any direction, the leverage of this manual pressure about either joint is substantial and the frictional resistance of the sleeve 51 is readily overcome.

With the lamp unit resting on a working desk, the arm 14 has a range of travel not in excess of ninety degrees from the vertical. The arm 13, the upper arm, could if desired be given a much greater range of movement. It is, however, preferred to provide the upper arm with a range of movement that approximates ninety degrees. For this purpose, the tubular portion 64 is curved as shown and, as a consequence, the movement of arm 13 is limited to the range between the full and dotted line positions in Fig. 1.

The forces in the present organization are distributed to provide for the proper counterbalancing of the load in all positions. For this purpose the friction sleeve in the upper arm is made to offer greater frictional resistance than the friction sleeve in the lower arm as by its heavier stock.

The manner in which the forces operate to maintain the lamp or other load unit in adjusted position will be best understood by reference to the diagrams in Figs. 14, 15, 16, and 17, which are specifically applicable to the specific

embodiment of the invention disclosed herein and will illustrate the principle involved.

Fig. 14 shows the position of maximum moment on the lower joint 40, as limited by the mechanical design embodied in the present preferred form. The spring 50 of the lower joint serves substantially to counterbalance the moment of the load about the joint 40. The lower friction sleeve in this position may be spoken of as supplying excess friction. The upper joint spring in this position supplies very little counterbalancing moment and upper friction sleeve supplies substantially the pressure needed to prevent the load unit from moving downwardly about the joint 15.

In Fig. 15, the lower joint friction sleeve supplies the needed friction acting against the lower joint spring and prevents it from raising the lower arm by its excess counter-balancing moment. In the upper arm the same situation exists, for here too, the spring is compressed so as to supply an excess counterbalancing moment which is balanced by the friction sleeve. Thus it is that in the position shown in Fig. 15 the springs exert their maximum moments which are partly counterbalanced by the friction.

Thus the lower arm spring is strong enough to counterbalance the moment of the load in Fig. 14, where the load exerts its greatest moment. In Fig. 15, the lower arm spring remains in the same degree of compression but the load moment is considerably reduced. So in this position the lower friction sleeve counterbalances the excess pressure or moment of the lower spring.

In Fig. 16 the lower arm spring supplies almost zero counterbalancing moment. In this position therefore, the lower friction sleeve supplies the entire counterbalancing moment to keep the lower arm vertical. The upper arm spring supplies most of the necessary moment to keep the upper arm in horizontal position and the upper friction sleeve shares the load and also supplies excess friction.

What was said about the lower spring and sleeve in the discussion of Fig. 16 is also applicable to Fig. 17. In this position the upper joint spring supplies excess counterbalancing moment which tends to move the upper arm to dotted line position. The upper friction sleeve supplies the frictional force to counteract the spring to hold the arm in the full line position.

Figs. 14 to 17 show the arms in critical positions. The other positions which are intermediate the positions shown involve the combinations of forces to maintain the load in adjusted position and to facilitate the movement of the load from one position to another.

The moment of the load about joint 15 decreases as the upper arm moves from position shown in Fig. 16 to its position in Fig. 17. During this movement the upper spring undergoes considerable compression and its counterbalancing moment increases considerably. The upper friction sleeve is heavier than the lower friction sleeve to overcome this excess of pressure by the upper spring under these conditions.

The coefficient of static friction of the friction sleeves is considerably greater than the coefficient of sliding friction. This assists considerably in the ease of manipulation of the present device.

In the preferred form of the invention shown herein, the upper spring has a reduced free length and heavier wire as compared with the lower helical spring.

I claim:

1. A support for a movable load unit comprising in combination, a base, a tubular bracket arm pivoted on said base, a load unit disposed within said arm, a friction element slidably carried by said arm and exerting outward pressure thereon, a link connected to said base and said friction element, and a resilient body exerting force against said friction element, said friction element and resilient body cooperating to counterbalance the weight of said load unit in all positions.

2. The support set forth in claim 1 in which the friction element comprises a resilient metal sleeve.

3. The support set forth in claim 2 in which the resilient body comprises a coil spring.

4. A support for a movable load unit comprising in combination, a base, an inner tubular bracket arm pivoted to said base, a friction element slidably disposed within said arm, a link connected to said base and said friction element, a resilient body disposed within said arm and exerting an upwardly directed force upon said friction element; an outer tubular bracket arm pivoted to said inner bracket arm, a friction element slidably disposed within said outer arm, a resilient body disposed within said outer arm and exerting an upwardly directed force upon said friction element, a link connecting said last named friction element and said inner bracket arm, and a load unit carried by said outer bracket arm; said links, friction elements and resilient bodies cooperating to maintain the load unit in any adjusted position.

5. The support set forth in claim 4, in which said friction elements and said resilient bodies are disposed intermediate the ends of the respective bracket arms thereby substantially freeing the pivots of any counterbalancing pressures.

6. A support for a movable mass, comprising in combination, a base, a standard supported on said base and carrying the mass at its free end; said standard having at least two jointed parts, each part comprising a tube with a longitudinal slit, a slidably split sleeve within and in frictional contact with the interior of each tube, said sleeve having an integral lug passing through said slit, a link pivoted at one end to said lug and at the other end to an adjacent part of said standard, and a resilient body disposed within each tube exerting pressure against one end of said sleeve.

7. A support for a movable mass, comprising in combination, a base, a standard supported on said base and carrying the mass at its free end; said standard having at least two jointed parts, each part having a hollow body portion, a slidably resilient sleeve within and in frictional contact with the interior of each body portion, a link pivoted at one end to said sleeve and at the other end to an adjacent part of said standard, and a coil spring disposed within said body portion and exerting resilient pressure against one end of said sleeve.

8. In combination, a base, a standard, and a swivel mounting for the standard on said base, said mounting comprising a stud fixed on said base, the stud having a circumferential groove, a two-part housing receiving one end of said standard and embracing said stud, the abutting faces of said housing having inter-engaging portions, pintles passing through said portions and holding said parts in fixed assembly, said housing having a lug entering the circumferential groove

in said stud, the pintles being directed generally parallel to the stud.

9. A swivel connection between a pair of elements comprising a stud fixed to one element, 5 a two-part housing carried by the other element and rotatably embracing said stud, the housing parts having inter-engaging portions, and pintles passing through said portions and holding said parts in fixed assembly, the pintles being directed generally parallel to the stud.

10. A swivel connection between a pair of elements, comprising a stud fixed on one element, a two-part housing carried by the other element and rotatably embracing said stud, the housing parts having two sets of inter-engaging portions, 15 pintles passing through said portions and holding said parts in fixed assembly, and inter-engaging means carried in part by said housing and in part by said stud serving to limit relative rotation of 20 said housing and stud and to hold the same in assembled relation, the pintles being directed generally parallel to the stud.

11. A swivel connection between two parts comprising two end elements carried by said parts and an intermediate element, one of said end 25 elements having a conical body portion, said intermediate element having a conical inner surface in engagement with said conical body portion, said intermediate and last named end elements having interengaging parts for holding said elements in assembled relation, the other end element and said intermediate element being connected to provide pivotal movement therebetween about an axis vertical to the axis of rotation between the intermediate and first end elements.

12. A support for a movable mass, comprising in combination, a base, a standard supported on said base and carrying the mass at its free end; said standard having two jointed tubular arms, a slidably split friction sleeve within each arm and in frictional contact with interior of the arm, a helical spring within each arm exerting force against one end of its associated friction sleeve, a link for each arm connected at one end to its sleeve and at the other end to a part of the standard adjacent the arm, the friction sleeve in the arm furthest removed from the base exerting a greater frictional pressure than the other friction sleeve.

13. A support for a movable load unit comprising in combination, a base, an inner bracket arm pivoted to said base, an outer bracket arm pivoted to said inner bracket arm, a friction element slidably carried by each arm, a helical spring carried by each arm in engagement with its friction element, a link connecting the friction element in the inner arm to the base, and another link connecting the friction element in the outer arm to the inner arm, whereby movement of the load unit relative to the base will cause the movement of at least one friction element relative to its arm and the transmission of a sliding force to it by its spring.

14. A support for a movable load unit comprising in combination, a base, a tubular bracket arm pivoted on said base, a load unit carried by said arm, a resilient friction sleeve disposed within said tubular arm and having its outer surface in frictional engagement with the inner surface of the tubular arm, a link connecting said sleeve to said base and serving to move said sleeve axially of the arm as the arm is moved relative to the base and a helical spring disposed within said arm in engagement with said sleeve and operable

by movement of the load unit to transmit a sliding force to said sleeve.

15. A support for a movable load unit comprising in combination, a base, an inner tubular arm pivoted to said base, an outer tubular arm pivoted to said inner arm, a slidable element disposed within each arm in frictional engagement with its wall, a helical spring disposed in each arm in engagement with its slidable element, a link connecting the slidable element of the inner arm to the base, and another link connecting the slidable element of the outer arm to the first arm, whereby movement of the load unit relative to the base will cause the transmission of a sliding force to at least one slidable element by its spring.
